APPAREL GARMENT

Raymond W. Bissell, Milford, Conn., assignor to
The Strouse Adler Company, New Haven,
Conn., a corporation of Connecticut

Application April 25, 1936, Serial No. 76,315

8 Claims. (Cl. 2-37)

This invention relates to an apparel garment such as a corset, girdle, or combination garment adapted to encircle the hips.

An object is the provision of a garment of this type, providing a distinctly effective restraining control over the back portion of the body while at the same time ensuring bending freedom, preventing "riding up" in various positions of the wearer, and avoiding undue strains upon garters and stockings.

These results I accomplish by a garment construction including elastic and non-elastic portions interrelated in a novel and effective manner. The invention further provides for the attainment of the foregoing advantages with a minimum amount of elastic fabric. It enables, moreover, the utilization of a non-elastic rear panel, with the production of a desirable and positive flattening effect upon the posterior portions of the wearer, without sacrifice of freedom of bodily movement or of the other advantageous features above noted.

Further objects and advantages will be pointed out hereinafter and will be apparent from a consideration of one embodiment of the invention, illustrated in the accompanying drawing, in which

Figure 1 is a perspective view of a garment viewed from the back,

Figure 2 is a perspective view of the major part of the same garment looking at the front, and

Figure 3 is a perspective view of a portion of the back of a similar garment but illustrating a modification.

The garment of Figs. 1 and 2 comprises a back panel 10, front panel 11, and two side panels 12, 13. The garment preferably extends downwardly from substantially the waist-line region of the wearer to such an extent that its lower edge 9 lies below the hips, although it is to be understood that the garment may be combined with a brassière or adapted in some other combination to extend around the body of the wearer above the waist.

The rear panel 10 is of non-elastic fabric and provides a positive restraining and flattening action upon the posterior portions of the wearer. The side panels 12, 13 are made of one-way stretch material including elastic yarn so arranged that the material is capable of stretching crosswise or generally horizontally of the wearer but not in an up and down or generally vertical direction. The front panel 11 preferably is of non-elastic material and tapers inwardly from top to bottom. The side panels are stitched or otherwise attached along their edges 14, 15 to

corresponding edges of the rear panel 10, and along their edges 16, 17 to the edges of the front panel 11.

The rear panel 10 is cut away at its lower side portions to provide the downwardly and inwardly inclined edges 18, 19 i. e., edges inclined downwardly and toward the center line of the back portion of the garment, while the lower portions of the side panels 12, 13 are similarly cut away to provide the downwardly and outwardly inclined edges 20, 21, respectively.

Between the respective pairs of edges 18 and 20, and 19 and 21, there are inserted in the lower rear portion of the garment triangular gores 22, 23. These gores are of one-way stretch material including elastic yarn so arranged that the material is capable of stretching up and down or in a generally vertical direction. Said gores may be attached in any suitable way, as by stitching, to the corresponding adjacent edges of the side and rear panels. Rear garters 24, 25 are attached to said gores as shown.

The front panel may include a gore or insert 26 of one-way stretch elastic material arranged to stretch horizontally. The front garters 27, 28 may be attached to the front panel on each side of said gore 26.

Bones 29, 30 may be inserted in suitable pockets in the front panel, if desired, to provide additional confining action at the front of the wearer.

The provision of the substantially non-elastic rear panel in combination with the horizontally elastic side panels and vertically elastic rear gores 22, 23 above described provides a desirable flattening and confining action upon the posterior portions of the wearer while enabling free bodily movement. The vertical stretchability of the gores 22, 23, provides a considerable flexing capacity in the rear of the garment which enables the garment to be firmly anchored to the figure in all positions and prevents the "creeping" or "riding up" which would otherwise occur. The elastic webbing of the garters 24, 25 in combination with the vertical elasticity of the gores, creates a particularly advantageous flexibility of garter action, obviating the imparting of undue strains to the garters and stockings.

It may be additionally observed that by virtue of the non-elastic material of the rear panel, an effective medium is provided wherein bones (such as those shown at 29, 30) may be inserted in suitable pockets to secure further flattening or restraining control at the back. On the other hand, these bones may be omitted where such additional control is not required. The provi-

sion of the non-elastic back panel in combination with the vertically stretchable gores thus results in a type of construction readily adaptable to any figure type, with the attainment of the required 5 confining action at the rear, while insuring comfort to the wearer and the avoidance of creeping of the garment and of overstrains on the stockings and garters.

A fastener 31 of the zipper type may be provided 10 between the upper portion of the front panel edge 17 and the adjacent side panel edge, which fastener, when opened, allows the garment to be easily pulled over the hips. A piece of soft material 32 may be stitched to the inside of the 15 side section 13 to protect the wearer against the metal of said fastener. If desired, a strip 33, provided with a hook and eye fastener and attached at one end to front panel 11 may be also employed to relieve the zipper 31 from some of 20 the strain.

Various modifications may be made within the scope of my invention. For example the zipper 31 may be extended to the full length of the garment, to provide a garment of the wrap-around 25 type or any other suitable fastening means may be employed. If desired, the gores may be made of two-way stretch fabric without sacrificing the advantages of the garment, although the cost of manufacture may be thereby increased. An example 30 of this is shown in Fig. 3 which illustrates a part of the lower portion of the back of a garment. The back panel 10a and side panel 12a of this garment are identical with the panels 10 and 12 of Figs. 1 and 2, and in all other respects this garment may be assumed to be like the garment of the preceding figures except that the gore 23a (and likewise the corresponding gore at the opposite side of the rear panel) is made of a two-way stretch fabric, e. g. contains 35 both horizontally-extending and vertically-extending elastic threads. The gores of these garments may be of any suitable shape and size.

The terms and expressions which I have employed are used as terms of description and not 45 of limitation, and I have no intention, in the use of such terms and expressions, of excluding any equivalents of the features shown and described or portions thereof, but recognize that various modifications are possible within the 50 scope of the invention claimed.

I claim:

1. A garment of the class described having 11 its back portion material substantially non-elastic in at least the vertical direction extending 55 from the lower edge of the garment upwardly at both sides of the centerline of the back to restrain posterior portions of the wearer and the side boundaries of which material, at at least its lower part, extend downwardly and toward 60 the centerline of the back of the garment, and also having in its back portion, at each side of said vertically-non-elastic material, material that is elastic in at least the vertical direction and that is connected to the adjacent boundary of 65 said substantially non-elastic material, at least at the lower part of the latter, so that vertically-elastic material is located between said substantially non-elastic material and the lower edge of the garment.

70 2. A garment of the class described having in its back portion a panel of material substantially non-elastic in at least the vertical direction and that extends from the lower edge of the garment upwardly to restrain posterior portions of the 75 wearer and the side edges of which, at at least

its lower part, extend downwardly and toward the centerline of the back of the garment, and, at each side of said vertically-non-elastic panel, a panel of material that is elastic in at least the vertical direction and that is attached to the 5 adjacent edge of said substantially non-elastic panel, at least at the lower part of the latter, so that vertically-elastic material is located between said substantially non-elastic panel and the lower edge of the garment.

3. A garment of the class described having a central back section substantially non-elastic in the vertical direction and extending substantially from at least the waist to the lower edge of the garment, and the side edges of which, at least at 15 its lower part, extend downwardly and toward the centerline of the back of the garment, and elastic material at each side of said back section extending substantially from the waist to the lower edge of the garment and attached to the 20 adjacent edge of the back section, thereby portions of said elastic materials being located between said back section and the lower edge of the garment as well as at both sides of said back section, said elastic materials being elastic in at 25 least the horizontal direction adjacent the waist and being elastic in at least the vertical direction in portions thereof between said back section and the lower edge of the garment.

4. The subject matter of claim 1 in combination 30 with hose supporters attached to those parts of the back portion which are elastic in the vertical direction.

5. A garment of the class described comprising a rear panel of substantially non-elastic fabric 35 extending substantially from at least the waist to the lower edge of the garment and the side edges of which, at at least its lower part, are inclined downwardly and inwardly toward the centerline of the garment, side panels of elastic fabric arranged to stretch only in a substantially horizontal direction, and gores of elastic fabric between the inclined edges of the lower portions of said rear panel and the lower edge of the garment, the fabric of said gores stretching in a substantial 40 vertical direction.

6. A garment of the class described comprising a rear panel of substantially non-elastic fabric extending substantially from at least the waist to the lower edge of the garment and the side 50 edges of which, at at least its lower part, are inclined downwardly and inwardly toward the centerline of the garment, side panels of elastic fabric arranged to stretch only in a substantially horizontal direction, gores of elastic fabric between the inclined edges of the lower portions of said rear panel and the lower edge of the garment, the fabric of said gores stretching in a substantial 55 vertical direction, and hose supporters attached to said gores.

7. A garment of the class described including a rear panel of substantially inelastic material extending substantially from at least the waist to the lower edge of the garment and the side edges of which, at at least its lower part, are inclined 60 downwardly and inwardly toward the centerline of the garment, and gores of vertically stretchable elastic material attached to said rear panel between the inclined edges of the lower portion of said rear panel and the lower edge of the 70 garment.

8. The subject matter of claim 1, characterized by the fact that said vertically elastic material is elastic substantially horizontally also.
